200,826

GROUND EFFECT MACHINE

Francis P. Bassett, Lockport, and John B. Chaplin, Williamsville, N.Y., and T. Desmond Earl, Niagara-on-the-Lake, Ontario, Canada, assignors to Bell Aerospace Corporation, Wheatfield, N.Y.

Filed May 8, 1964, Ser. No. 79,892

Term of patent 14 years

(Cl. D71—1)

FIG. 1

Des. 200,826

PAGE 2

FIG.2

FIG.3

FIG. 4

FIG. 5

FIG. 1 is a three-quarter front perspective view taken slightly from above of a ground effect machine showing our new design;

FIG. 2 is a top plan view thereof;

FIG. 3 is a side elevational view thereof;

FIG. 4 is a front elevational view thereof; and

FIG. 5 is a rear elevational view thereof.

We claim:

The ornamental design for a ground effect machine, as shown.
